UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

ROTARY PERFECTING SHEET-PRINTING MECHANISM.

1,242,908.

Specification of Letters Patent. Patented Oct. 16, 1917.

Application filed January 22, 1918. Serial No. 748,553.

To all whom it may concern:

Be it known that I, HOWARD M. BARBER, a citizen of the United States, and resident of Stonington, in the county of New London and State of Connecticut, have invented a new and useful Improvement in Rotary Perfecting Sheet-Printing Mechanism, of which the following is a specification.

The object of this invention is to prevent offsetting in rotary perfecting sheet printing machines and comprises novel means for preventing the offsetting of the first printed side of the sheet onto the second impression cylinder during the printing of the other side of the sheet and also preventing the offsetting of the perfected sheets on one another in the delivery. This invention more particularly consists in providing means whereby the second impression cylinder is caused to take first a slip sheet and then a sheet printed on one side, carry the two through the second printing operation and finally deliver the perfected sheet and the slip sheet together.

A practical embodiment of my invention is represented in the accompanying drawings, in which—

Figure 1 and Fig. 1^a is a view in side elevation partly in section of so much of a rotary perfecting sheet printing machine as will give a clear understanding of this present invention,

Fig. 2 and Fig. 2^a represents the same in vertical section taken from front to rear,

Fig. 3 represents the driving means for the printing sheet feeding mechanism, and

Fig. 4 represents the driving means for the slip sheet feeding mechanism.

The printing mechanism for printing on the first side of the sheet is herein shown as comprising a plate cylinder 1 and its impression cylinder 2. The printing mechanism for printing upon the opposite side of the sheet is herein shown as comprising a plurality of plate cylinders 3 and their impression cylinder 4.

The means for feeding the printing sheets to the first impression cylinder 2 includes a feeding cylinder 5. The means for feeding the slip sheets to the second impression cylinder 4 includes the cylinder 6.

The portion of the delivery mechanism which is shown herein includes the first delivery reel 7, which coacts with the second delivery reel 8, which delivery reel 8 will deliver the sheets to the balance of the delivery mechanism, not shown herein.

ivery reel 8 which coacts with the first delivery reel 7.

Means are shown for feeding the sheets from the printing sheet feed table 9, to the sheet stop 10 at the sheet feeding cylinder 5, which means comprises the endless tape carriers 11, 12, the feeding rollers 13 and the drop rollers 14 arranged to coact with the rollers 13 at the proper intervals. A sheet stop 15 is also provided at the table 9, which sheet stop is carried by the movable support 16 for the drop rollers so that the sheet stop 15 is moved into and out of operative position as the drop rollers are moved out of and into operative position.

Similar means may be employed for feeding slip sheets from the feed table 17 to the stop 18 at the slip sheet feeding cylinder 6, which means comprises the endless tape carriers 19, 20, the sheet stop 21, the feeding rollers 22 and the drop rollers 23 arranged to coact with the rollers 22.

While I have described the printed sheets as being fed from the table 9, it is to be understood that the sheets may be cut and fed from a roll, if so desired.

The printing sheet feeding cylinder 5 is provided with a set of grippers 24 which is arranged to take the sheets from the tape carrier 11 and transfer them to the grippers 25 on the first impression cylinder 2.

The slip sheet feeding cylinder 6 is provided with a set of grippers 26 which is arranged to take a slip sheet from the endless tape carrier 19 and transfer the sheet to a set of grippers 27 on the second impression cylinder 4. The set of grippers 27 after it has taken the slip sheet from the set of grippers 26 will take a first side printed sheet from the set of grippers 25 on the first impression cylinder 2 and convey the two sheets with the slip sheet interposed between the printed side of the printed sheet and the cylinder and convey the two sheets beneath the plate cylinders 3. The first delivery reel 7 is provided with a set of grippers 28 arranged to take the perfected sheet and the slip sheet from the set of grippers 27 and transfer the same to the grippers 29 of the second delivery reel 8, which delivery reel 8 will deliver the sheets to the balance of the delivery mechanism, not shown herein.

In the accompanying drawings, I have shown the cylinders 5, 2, 6, 7 and 8 as each provided with one set of grippers and the

cylinder 4, as provided with three sets of grippers.

The movement of the sheet stop 10 is controlled by a cam 30 and the movement of the sheet stop 18 is controlled by a cam 31.

A tumbler cam mechanism 32 is provided for opening and closing the grippers 24 of the printing sheet feeding cylinder 5 to transfer the sheet from its feeding tapes to the first impression cylinder 2. A fixed cam 33 is provided for opening the grippers 25 to transfer the first side printed sheet to the second impression cylinder grippers and to hold the said grippers 25 open to receive a succeeding printing sheet from the feeding cylinder 5. A tumbler cam mechanism 34 is provided for opening and closing the grippers 26 of the slip sheet feeding cylinder 6 to transfer a slip sheet from the tape carrier to the second impression cylinder.

A fixed cam 35 is arranged in position to open the grippers 27 to deliver a perfected sheet and a slip sheet together to the first delivery reel 7 and to keep the grippers open to receive a slip sheet from the cylinder 6. A fixed cam 36 is arranged in position to open the grippers 27 to receive a first side printed sheet from the first impression cylinder 2.

Pressure rollers 37 are arranged in position to keep the slip sheet in register while the grippers 27 are being opened to receive a first side printed sheet from the first impression cylinder 2.

A fixed cam 38 is provided for opening the grippers 28 of the first delivery reel 7 to transfer a perfected sheet and a slip sheet together to the second delivery reel 8 to keep the said grippers open to receive a succeeding pair of perfected and slip sheets from the grippers 27.

A fixed cam 39 is provided for opening the grippers 29 to receive the perfected and slip sheets from the reel 7 and deliver the same.

The several cylinders and reels are driven at the proper speeds with respect to one another through the trains of gearing 41, 42, 43, 44, 45, 46, 47 and 48.

The shaft 49 of the printing sheet feeding cylinder 5 has a driving connection with the sheet feeding means through the train of gearing 50, 51, 52, 53, 54, 55, 56, 57, 58, and similarly the shaft 59 of the slip sheet feeding cylinder 6 has a driving connection with its feeding means through the train of gears 60, 61, 62, 63, 64, 65, 66, 67, 68.

The drop rollers 14 and the sheet stop 15 are brought into and out of operative position by a cam 69 on the shaft 49 and its connecting parts and the drop rollers 23 and sheet stop 21 are moved into and out of their operative position by a cam 70 on the shaft 59 and its connecting parts.

Copies of this patent may be obtained for five cents each, by addressing the "Commissioner of Patents, Washington, D. C."

While I have shown a first printing mechanism arranged to print one color and a second printing mechanism arranged to print a plurality of colors, it is to be understood that I contemplate using this invention in connection with single or multi-color work, as desired.

It will be seen that by introducing slip sheets between the second cylinder and the freshly printed side of the printed sheet as it comes from the first printing mechanism, the slip sheet will act as an offset sheet and will prevent the ink from the first side printed sheet from building up upon the top sheet of the make-ready on the second impression cylinder. It will also be seen that this slip sheet by being delivered together with the perfected printed sheet serves to prevent offsetting from one printed sheet onto another printed sheet in a pile.

It is evident that slight changes might be resorted to in the form, construction and arrangement of the several parts without departing from the spirit and scope of my invention; hence I do not wish to limit myself strictly to the structure herein set forth, but

What I claim is:—

1. In a rotary perfecting sheet printing machine, printing mechanisms for printing on both sides of a sheet including first impression and plate cylinders and second impression and plate cylinders, a printing sheet feeding cylinder arranged to feed a sheet to the first impression cylinder and a slip sheet feeding cylinder arranged to feed a slip sheet directly to the second impression cylinder, the first impression cylinder being arranged to transfer the first side printed sheet to the second impression cylinder on top of the said slip sheet.

2. In a rotary perfecting sheet printing machine, printing mechanisms for printing on both sides of a sheet including first and second impression cylinders, a printing sheet feeding cylinder arranged to feed a sheet to the first impression cylinder and a slip sheet feeding cylinder arranged to feed a sheet to the second impression cylinder, the first impression cylinder being arranged to transfer the first side printed sheet to the second impression cylinder on top of the said slip sheet, the second impression cylinder being arranged to carry the two sheets through the second printing operation and deliver them together.

In testimony that I claim the foregoing as my invention, I have signed my name, in presence of two witnesses, this fourteenth day of January, A. D. 1913.

HOWARD M. BARBER.
